Primary Examiner — George A Bugg*Assistant Examiner* — Tamara L Hahn(74) *Attorney, Agent, or Firm* — Abelman, Frayne & Schwab(57) **CLAIM**

The ornamental design for a bin, as shown and described.

DESCRIPTION

FIG. 1 is a front, right, and top perspective view of a bin showing the new design;

FIG. 2 is a right side elevational view thereof;

FIG. 3 is front view thereof;

FIG. 4 is a left side elevational view thereof;

FIG. 5 is a rear view thereof;

FIG. 6 is a top view thereof; and,

FIG. 7 is a bottom view thereof.

The broken line showing of the bin is for the purpose of illustrating portions of the article that form no part of the claimed design.
